US00D503160S

(12) **United States Design Patent** (10) Patent No.: **US D503,160 S**
(45) Date of Patent: **** Mar. 22, 2005**

(54) **FLAT-PANEL DVD PLAYER WITH DISPLAY**

(75) Inventor: **Juen-Tien Peng, Chung Li (TW)**

(73) Assignee: **Action Electronics Co., Ltd., Chung Li (TW)**

(**) Term: **14 Years**

(21) Appl. No.: **29/199,552**

(22) Filed: **Feb. 18, 2004**

(51) LOC (7) Cl. **14-03**

(52) U.S. Cl. **D14/129**

(58) Field of Search **D14/125-134, D14/239, 371, 374-376; 312/7.2; 348/836, 838, 180, 184, 325, 739; 341/12; 248/917-924, 465; 345/104, 133, 156, 168, 87, 173; 720/605, 669, 600, 655; 369/99, 197; 455/344-347**
